Attn: S.

UNITED STATES PATENT OFFICE.

FRANK S. EGLOFF, OF RIVERSIDE, ILLINOIS.

OIL BURNER.

Application filed February 14, 1924. Serial No. 692,661.

To all whom it may concern:

Be it known that I, FRANK S. EGLOFF, a citizen of the United States, residing at Riverside, in the county of Cook and State of Illinois, have invented certain new and useful Improvements in Oil Burners, of which the following is a specification.

This invention which relates to an oil burner is designed particularly for use with building heating plants of various kinds. In its construction are embodied numerous features of improvement having to do with simplicity in the construction and assembly of its several components, and with general accessibility or removability of its principal units for purposes of repair, replacement, cleaning, or what not. In addition, the several parts of this burner are so formed and arranged as to co-operate in effecting a complete combustion of fuel oil, and for this purpose provision is made for supplying air to the flame in a definitely advantageous manner. Various objects of this kind are contemplated in the present invention, also others which will more fully hereinafter appear.

An exemplification of this invention is set forth in the accompanying drawing wherein—

Figure 1 is a vertical section through the burner showing the interrelation of its several components; and

Fig. 2 is a plan view thereof with the flame and ring deflectors removed.

The present burner comprises four major units—a burner head A whereon is rested a flame deflector B, a frame C in which the burner head is mounted, and a ring D loosely carried in the frame. These several parts, when assembled as shown in Fig. 1, are adapted to be placed within a furnace wherein pipe connections are also carried to supply or remove oil as required.

The burner head is in the general form of a hollow cone having an inner cylindrical wall 3 uniting with a bottom 4 which, in turn, is united with the lower edge of an outer cone wall 5 having its upper edge terminating, by preference, slightly below the upper edge of the cylindrical wall 3. Between the upper edge of the cone wall 5 and the cylindrical wall 3 is an opening 6, shown as annular, communicating with the chamber 7 which is formed interiorly of the burner head by the walls and bottom just described. A fuel inlet pipe 8 is connected

with the burner head so as to deliver oil into this chamber.

The conical wall 5 of the burner head is smooth and relatively steep, and near its base is outwardly flared as at 9 to provide a shoulder having a lesser inclination; and extending below and outwardly from the cone base is an annular trough 10 surrounded by a peripheral wall 11 whereon are formed a plurality of cam-shaped ribs 12, constituting in effect a multiple cam. A drain pipe 13 connects with the trough, as shown. An undercut shoulder 14 is further formed on the peripheral wall, and in complementary relation thereto are certain webs 15 projecting inwardly from the frame C. This frame which is of plate-like structure provides through the medium of its several webs a seat in which the burner head is rested, a plurality of arc-shaped openings 16 having a substantial area intervening therebetween. Each of these webs, as shown, is provided with a lug 17 adapted to engage with the under side of the shoulder 14 to thereby afford support for the burner head. By rotating the head to the position shown in Fig. 2 the cam ribs will be caused to engage with certain grooves 18 that are provided in the webs so as to interlock the head with the frame. Manifestly the head may be removed after being turned in a reverse direction sufficiently to disengage the cam ribs from the webs of the frame.

An upstanding shoulder 19 is provided on the frame in such a manner as to form an annular seat whereon the ring D may be loosely rested. The walls of this ring, according to my invention, extend upwardly and inwardly from its seat so as to provide an inclined portion 20 adapted to deflect toward the cone walls 5 the air which proceeds upwardly through the openings 16. This is of importance for reasons which will presently appear.

Supported on the burner head is the flame deflector B which may have the general form of an inverted cone as shown. It is provided with suitable webs 21 which may be rested upon the upper edge of the cylindrical walls of the burner so that its outwardly flaring surface 22 will be suitably spaced therefrom. For convenience in handling, an eye 23 is provided on the upper side of the deflector, as shown.

An oil burner answering to the above description possesses certain very definite ad-

vantages both from the standpoints of manufacture and assembly, and of operation as well. Its several parts may be readily installed within a furnace, the frame alone being fixedly secured in place therewithin. Adjacent the outer periphery of the frame I have provided several elongated arcuate slots 24 through which, at any point intermediate of their ends, one or more attaching bolts 10 (not shown) may be inserted for securing purposes. Manifestly the ring D may be lifted off of its seat without any preliminary operation whenever its removal is desired. Likewise the flame deflector may be taken off 15 of the burner head by a similar operation. By first unlocking the burner head through a rotary motion, it may be removed from the frame, either through its upper or lower side. In carrying out this latter operation, 20 it is contemplated that the two oil pipes should be disconnected, preferably at the union (not shown) which, in ordinary practice, is located close to the furnace door.

The present burner may use advantageously any suitable distillate whose gravity range is, say, from 36 to 42 degrees Baume. The chamber 7 is filled from the supply pipe so that the oil therein may burn at the opening 6, the oil burning at that point only producing the minimum amount of flame and heat. With increase in the flow of oil to the burner, a portion of the fuel which overflows upon the relatively steep conical walls 5 will spread and break up, the lighter 30 part being consumed before reaching the base of the cone; the flow of the heavier portion of the fuel is retarded at the shoulder of the cone, being consumed at that point or above so as to produce the maximum 40 amount of flame and heat, the flame being spread in a desirable manner by means of the deflector B.

In case any valve controlling the flow of oil through the intake pipe is opened accidentally or otherwise, so as to allow oil to flow through the burner without being ignited, or in case of an excess of oil being fed to the burner, any such excess or overflow is collected at the trough 10 from whence 50 it flows through the outlet pipe 13 into a cup (not shown) which may operate a drip valve for shutting off the oil passing through the supply pipe.

The combustion of the oil is supported in a very effective manner, by air being conducted to the flame from both its inner and outer sides. Interiorly of the cylindrical wall 3 a quantity of air passes up to form an air curtain between the deflector B and the flame below, thus tending to ensure a 60 complete combustion of the oil with a consequent minimization of carbonization and vibration.

The main supply of air to the burner which passes through the openings is deflected by the inclined wall 20 of the ring D and is thereby controlled as a volume, velocity and point of contact with the oil. In this manner a proper mixture of air with oil is assured, such as is necessary for complete 70 combustion of the fuel. By the use of cone walls which are relatively steep and smooth, I am able to secure a maximum amount of fuel spread, with a minimum amount of thickness of the oil flow exposed to the current of air which passes through the openings 16. The result of this is a clean combustion and maximum efficiency of the fuel used. The oil supply inside the burner cone is preheated to the boiling point by the 80 heat from the burning oil on the exterior of the burner cone, thereby further increasing the general efficiency of the apparatus. A burner answering to the preceding description may be advantageously operated with a natural draft of air and gravity feed of fuel, thus conducting to the general simplicity of the mechanism.

I claim:

An apparatus of the kind described in which is comprised a chambered burner head having smooth outer conical walls in association with inner cylindrical walls between which is an annular space adjacent their upper edges, means for delivering a quantity of oil through the chamber of the burner head and down upon the smooth outer conical walls thereof, means adjacent the base of the conical walls for retarding the downward flow of oil thereupon, also other means for collecting oil which drains past said retarding means, and means for directing air against the conical walls of the burner head whereby to support combustion upon the outer side thereof, substantially as described.

FRANK S. EGLOFF.
